QUATERNARY INDOLE DERIVATIVES AND
THEIR MANUFACTURECurt Engel, Saint Louis, France, and Kurt
Pfahler, Riehen, near Basel, Switzerland, as
signors to J. R. Geigy A. G., Basel, SwitzerlandNo Drawing. Application April 9, 1940, Serial No.
328,796. In Switzerland May 19, 1937

2 Claims. (Cl. 260—319)

This application is a continuation-in-part of our application Ser. No. 207,154, filed May 10, 1938.

In the U. S. Patent 2,180,801 there is described a method of converting derivatives of the dihydro indole series into water-soluble bodies by treating with sulphonating agents, under suitable conditions, compounds of the following general structure:

which contain in position 2 an aliphatic or alicyclic substituent with more than 5 carbon atoms and which may be substituted in the free positions of the benzene nucleus in any desired manner and in the remaining free positions 1 and 3 by alkyl-, aralkyl- or aryl-groups. These novel sulphonic acids and their salts are used as wetting, dispersing, emulsifying and impregnating agents and as detergents, and in particular may be used as lime soap emulsifying agents.

As a result of further study in this field of dihydroindole derivatives it has now been found that new and valuable dihydroindoles are obtained if the water solubility is produced, not by the introduction of sulphonic acid groups, but by means of quaternary N-atoms.

As in the case of the U. S. Patent 2,180,801, the invention starts from the assumption that in the dihydroindole body of the general structure

there is an aliphatic or alicyclic substituent containing more than 5 carbon atoms, in the position 2. The remaining positions can be substituted in the manner set forth in the said Patent 2,180,801.

The novel compounds are made by exhaustively alkylating and/or aralkylating the dihydroindole compounds containing in 2 position a radical with more than 5 carbon atoms.

The products obtained in this way may be used as valuable assistants in the textile industry or in other branches of industry in which such assistants are used. A particular property of the new compounds, which may be mentioned by way of example, is that these compounds for the most part form insoluble precipitates with

dyes containing acid groups, so that they are suitable for rendering dyeings fast to water. Finally, it is worth while pointing out that a number of the novel products may also be used as plasticizers, as carbonizing, bactericidal and fungicidal agents.

As in the said Patent 2,180,801 dihydroindoless can quite generally be employed as the raw material for the present process, and these can be readily obtained by known methods, inter alia by splitting off water from suitable acylated o-alkyl- or -aralkyl-substituted aniline derivatives with sodium alcoholate (according to Madelung, Ber. d. deutschen chem. Ges. 45, p. 1128), or by means of sodium amide (per Verley, Bull. de la Soc. Chim. vol. 35, pp. 1039-40 (1924) and vol. 37, pp. 189-91 (1925) and German patent specification No. 479,283) and reducing the indoles thus obtained. Other methods of preparing dihydroindoless and their substitution products may equally well be employed however.

Instead of the catalytic hydrogenation of the indoles, any other known method of producing hydrogenized indoles can, however, be used with equal success.

The following examples illustrate the invention.

Example 1

34 g. of 2-heptadecyl-2:3-dihydroindole, obtained in known manner from 2-heptadecylindole, for example by catalytic hydrogenation with nickel, are dissolved in 100 ccs. of chlorobenzene and 17 g. of anhydrous sodium carbonate are added. 20 g. of dimethylsulphate are dropped in at 100° C. and the whole is stirred for 12 hours. Thereupon a further 20 g. of dimethylsulphate are run in drop-wise and the whole is kept a further 6 hours at 120° C. Thereafter the soluble portion is filtered off from the undissolved inorganic salts, the chlorobenzene is distilled off by means of steam and the aqueous solution evaporated under a vacuum. A wax-like semi-solid mass is obtained which forms a colorless solution in water. The compound corresponds to the formula

By replacing the first quantity of dimethylsulphate by equivalent parts of diethylsulphate or by replacing all the dimethylsulphate by the corre-

sponding ethyl compound, quaternary dihydro-
indoles with quite similar properties are obtained.

Example 2

34 g. of 2-heptadecyl-2:3-dihydroindole are dissolved in chlorobenzene and anhydrous sodium carbonate added as in Example 1. 20 g. of dimethylsulphate are dropped in and the whole stirred for 12 hours. 20 g. of benzylchloride (or also 27 or 30 g. of the bromide of technical stearyl- or dodecyl alcohol) are then added in drops and heated to 140° C. for 6 hours. After the salts have been filtered off, the chlorobenzene and excess of benzylchloride are removed by steam. The aqueous solution obtained may be etherised and evaporated to the dry state under a vacuum. A final product having similar properties to the product of Example 1 is obtained, and aqueous solutions of the product likewise have a high foaming capacity. The formula of the product of the present example is the following:

Example 3

34 g. of 2-heptadecyl-2:3-dihydroindole are dissolved in 100 ccs. of chlorobenzene, 17 g. of anhydrous sodium carbonate added, 20 g. of dimethylsulphate added in drops at 100° C. and the whole is stirred for 12 hours. 15 g. of chloracetic ethyl or methyl ester are then added gradually and the mixture heated to 140° C. for 6 hours. After the salts separating out have been filtered off, the chlorobenzene is distilled off by means of steam and, where required, the aqueous solution obtained is etherised and evaporated to dryness under a vacuum. A waxy mass, readily soluble in water, is obtained.

Example 4

34 g. of 2-heptadecyl-2:3-dihydroindole are, as described in the above example, first treated with 20 g. of dimethylsulphate at 100° C. for 12 hours, and then 12 g. of glycerin α -chlorhydrin is added drop by drop and the whole heated 6 hours to 120° C. After the salts have been filtered off, the chlorobenzene is distilled off with steam and, if desired, the aqueous solution is separated from insoluble impurities by filtration. The final product, which is obtained as set forth above, is a viscous oil of good capillary properties.

2-heptadecenyl- or 2-undecyl-2:3-dihydroindole or the numerous other starting materials set out in the U. S. Patent 2,180,801 may be used in place of the heptadecyldihydroindole employed in the above examples.

There may be named: The indoles derived from the o-toluidides of stearic, palmitic, oleic acid,

hydrogenized codliver oil fatty acid, hydrogenized soya bean fatty acid, palm nut oil fatty acid, coconut fatty acid, naphthenic acid, resin acid, campholic acid, fencholic acid, cyclohexane-carboxylic acid and so on; the corresponding dihydroindoless are obtainable therefrom by known methods of hydrogenation.

Instead of ortho-toluidine there may be used as parent material ortho-aminoethylbenzene, 10 meta- or paraxylidine, mesidine or other homologues of ortho-methyl-aminobenzene.

Example 5

44 g. of ethylene oxide are reacted on 28 g. of 2-undecyl-2:3-dihydroindole in a closed vessel at 100-120° C. 20 g. of this reaction product are dissolved in 20 ccs. of toluene and 17 g. of anhydrous sodium carbonate are added. 20 g. of dimethylsulphate are added in drops at 100° C. and the whole stirred for 12 hours. Thereupon, a further 20 g. of dimethylsulphate are added in drops and the whole is heated at 120° C. for 6 hours. After filtering off the salts of the toluene is removed by steam distillation and the aqueous solution obtained is evaporated to dryness under a vacuum. A semi-solid, waxy mass is obtained.

What we claim is:

1. The colorless quaternary dihydro-indoles of the formula

wherein R represents an alkyl group containing more than 5 carbon atoms; Z represents a member of the group consisting of methyl and ethyl; X and W represent radicals derived from a reactant of the formula X-W selected from the group consisting of $\text{CM}_3-\text{SO}_4\text{CH}_3$, $\text{C}_6\text{H}_5-\text{SO}_4\text{C}_2\text{H}_5$, $\text{Cl}-\text{CH}_2\text{COOCH}_3$, $\text{Cl}-\text{CH}_2\text{COOC}_2\text{H}_5$, $\text{Cl}-\text{CH}_2\text{CHOHCH}_2\text{OH}$ and $\text{Cl}-\text{CH}_2\text{C}_6\text{H}_5$ wherein the first-named radical constitutes X and the second-named radical constitutes W; Z represents a member of the group consisting of H and CH_3 ; and n represents one of the integers 1 and 2.

2. The colorless quaternary dihydroindole of 50 the following formula

being a wax-like semi-solid mass forming colorless aqueous solutions of high capillary activity.
